(57) **CLAIM**

The ornamental design for a smart WiFi adapter with dual USB port, as shown and described.

DESCRIPTION

FIG. 1 is an isometric view of a smart WiFi adapter with dual USB port showing my new design;

FIG. 2 is a front view thereof;

FIG. 3 is a back view thereof;

FIG. 4 is a top view thereof;

FIG. 5 is a bottom view thereof;

FIG. 6 is a right side view thereof; and,

FIG. 7 is a left side view thereof.

The broken lines in the drawings are for the purpose of illustrating portions of the smart WiFi adapter with dual USB port that form no part of the claimed design.

1 Claim, 4 Drawing Sheets
